BABY CARRIAGE HOOD

John O. Beynon, Waterloo, Ontario, Canada, assignor to Sunshine Waterloo Co. Limited, Waterloo, Ontario, Canada

Application December 20, 1950, Serial No. 201,746
In Canada December 22, 1949

3 Claims. (Cl. 296—110)

1

This invention relates to improvements in the construction of baby carriage hoods and more particularly to improvements in the lining of carriage hoods.

The principal object of the invention is to improve the manner of fastening the inner lining to the hood frame to eliminate the objection of and possible danger from any brads or rivets projecting within the hood whereby a more pleasing and desirable hood interior is presented.

Another important object is to eliminate objectionable seams within the hood.

A further important object is to provide an improved inner lining for collapsible carriage hoods which will permit collapse of the hood without obstruction thereto and which, with the hood extended, will present an unwrinkled lining surface yieldable under impact to prevent harm to the baby's arm or hand striking thereagainst.

Another object of the invention is to provide a novel lining arrangement to increase the weather insulating of the hood.

The principal feature of the invention resides in hanging the inner lining from a fabric loop encircling an intermediate frame bar to provide a flexible intermediate lining suspension and securing the lining panel sections on either side of the intermediate suspension to the hood adjacent the upper front and bottom rear edges respectively whereby rivets, bolts or other holding means for the outer covering, as well as the frame bars, are concealed.

A further important feature consists in folding the inner lining at the intermediate suspension to conceal the stitching, securing the lining to the suspending loop.

A still further feature of importance consists in securing the edges of the lining panel sections remote from the intermediate suspension in the same seams, securing the outer fabric or covering to the outermost frame bars.

These and other objects and features will be apparent from the following description in conjunction with the accompanying drawings in which

Figure 1 is a mid-vertical sectional view through a collapsible baby carriage hood provided with an inner lining suspension in accordance with my invention.

Figure 2 is an underside plan view of the hood of Figure 1.

Figure 3 is an enlarged vertical sectional detail taken through the intermediate frame bar from which the lining is suspended.

Figure 4 is a view similar to Figure 3 but show-

2

ing the inner lining made up of separate lining sections in place of the single lining section of Figure 3.

Figure 5 is an enlarged vertical sectional detail through one of the outermost frame bars showing the manner in which the lining panel section edge remote from the intermediate suspension is secured in the same seam that secures the outer covering fabric.

The drawings represent the embodiment of my novel lining suspension on a collapsible baby carriage hood but it will be understood that it may be used on any hood construction within the scope of my invention.

15 The hood illustrated is formed from a plurality of pivotally connected U frame bars comprising the outer frame bars 1 and 2 forming the bottom and forward edges of the hood respectively, and the main intermediate frame bar 3 and auxiliary intermediate frame bars 4.

15 Stretched over these frame bars is the outer covering or fabric 5 which as shown is secured to the outer frame bars 1 and 2 by looping these frame bars and stitched along 6 to form the receiving loop 7.

20 The outer covering 5 is normally secured to the intermediate frame bars by drive screws 8 or other equivalent holding means and in normal hood constructions these bolts are used additionally as the holding means for the inner lining used to conceal the frame bars.

25 Such previous normal constructions present an objectionable appearance from the interior of the hood in that the holding means 8 is exposed through the inner lining and such holding means are liable to cause harm to a baby's hand or arm striking thereagainst. Further, since the extent to which the inner lining and the outer covering become stretched in use it is difficult or impossible with present methods of securing the inner lining to prevent the inner lining surface from becoming wrinkled or presenting a matted appearance.

30 The present invention overcomes all of the disadvantages by affording the novel inner lining suspension, particularly illustrated in Figures 1, 3 and 4. The lining suspension comprises a sleeve or loop 9 of flexible fabric or the like received on the bight or transverse section 10 of the intermediate frame bar 3. Secured to this loop 9 is the inner lining indicated at 11 and 12, 11 being the lining panel section extending to adjacent the bottom frame bar 1 and 12 being the lining panel section extending to adjacent the

40 forward frame bar 2. These lining panel sec-

45

tions 11 and 12 suspended from the loop 9 may be either formed from a single fabric piece, as shown in Figure 3, or may constitute separate fabric pieces, as shown in Figure 4.

Preferably the seam 13 connecting the lining panels 11 and 12 to the loop 9 is concealed and to this end it will be seen that the panel sections are overlapped along a transverse length as at 14, and the seam 13 is provided by stitching through the overlap 14 and through the fabric of the loop 9 to both form the loop and secure the lining thereto.

The overlap 14 has the outer surfaces of the lining panels contiguous so that the one panel, in this case panel 12, must be folded back on itself in being extended to the forward frame bar, the fold at 15 providing for the concealment of the seam 13. Thus the objectionable transverse seam is completely concealed.

It will be seen from Figure 1 and Figure 5 that the edges of the lining panels 11 and 12 remote from the intermediate suspension from the loop 9 are secured to the loops 7 of the outer covering by the same stitching 6 that forms these latter loops. It will be seen that the loop 9 affords a flexible suspension of the inner lining from the intermediate frame bar 3, and the lining panels hanging from the loop 9 are spaced from the frame bars, affording concealment, not only for these bars but also for the rivets or bolts 8.

In the extended position of Figure 1, it will be seen that the lining panel sections 11 and 12 are pulled taut to eliminate any wrinkles therefrom yet being spaced from the frame bars and rivets 8, and being simply stretched surfaces they are yieldable to prevent injury to any part of the baby's body striking thereagainst.

The stretched lining surfaces, being spaced both from the frame bars and the outer covering 5, afford the insulating air pockets 16 which serve to increase the resistance to penetration of heat or cold through the hood.

Completing the lining are the side panels 17 which may be either separate from or integral with the lining panels 11 and 12, and as shown in Figure 1 the hood illustrated is provided with the weather-protecting hood extension 18.

With a lining suspended in accordance with my invention it will be seen that a very pleasing hood interior is presented by the unwrinkled angularly arranged lining panels 11 and 12, which not only afford a decorative covering of all previously exposed objectionable holding means but also afford a protective interior for the baby.

It will be understood of course that modifications may be made in the precise form of hanging suspension within the spirit or scope of my invention.

What I claim as my invention is:

1. In a collapsible baby carriage hood of the type having a frame comprising a plurality of U-shaped frame bars inter-connected at their ends and angularly disposed with at least one frame bar constituting an intermediate frame bar and angularly arranged between frame bars inclined adjacent to the vertical and adjacent to the horizontal to define the forward and bottom edges of the hood respectively, a flexible covering spanned over the frame bars and formed with loops encircling the frame bars defining the forward and bottom edges of the hood, an inner lining of flexible material extending between said loops, means securing said covering loops in

frame bar encircling position and securing said lining to said covering loops, flexible suspension means carried by said intermediate frame bar, said lining having, intermediate its connections to said covering loops, a transverse lapped portion overfolded on an adjacent lining portion, and means securing said lapped lining portion to said flexible suspension means with the lining portion over which said lapped portion is folded concealing said securing means.

2. In a collapsible baby carriage hood of the type having a frame comprising a plurality of U-shaped frame bars inter-connected at their ends and angularly disposed with at least one frame bar constituting an intermediate frame bar and angularly arranged between frame bars inclined adjacent to the vertical and adjacent to the horizontal to define the forward and bottom edges of the hood respectively, a flexible covering spanned over the frame bars and formed with loops encircling the frame bars defining the forward and bottom edges of the hood and presenting double thicknesses of covering material at the edges of said latter frame bars, means securing said flexible covering to said frame bars, a flexible suspension carried by an intermediate frame bar and secured thereto by the means securing said flexible covering, an inner lining of flexible material extending between said loops, means securing said covering loops in frame bar encircling position and securing said inner lining to the double thickness of covering material presented by said loops, said lining having, intermediate its connections to said covering loops, a transverse portion lapped on itself and overfolded on an adjacent lining portion, and means securing said lapped lining portion to said flexible suspension means.

3. In a collapsible baby carriage hood, the combination with a plurality of pivotally connected outer and intermediate U-shaped frame bars, an outer covering arranged over said frame bars, and means securing said outer covering to said frame bars, of a loop of flexible material encircling the bight of an intermediate frame bar to which said covering is secured, and an inner lining in the form of lining panel sections secured adjacent the edges of said hood to said covering and suspended thereby adjacent said outer frame bars, said lining panel sections being overlapped with the overlap being folded back over the top of one of said sections and stitched to said fabric loop to be flexibly suspended thereby from said intermediate frame bar, said section over which the overlap is folded concealing said stitching from the interior of said hood.
